[57] **CLAIM**

The ornamental design for a pool sweeper, as described and shown.

DESCRIPTION

FIG. 1 is a front elevational view of a pool sweeper showing my new design;

FIG. 2 is a top plan view thereof;

FIG. 3 is a bottom plan view thereof;

FIG. 4 is a side elevational view thereof, the opposite side being a mirror image; and,

FIG. 5 is a top perspective view thereof.

The hoses are shown broken away to indicate indeterminate length.
